UNITED STATES PATENT OFFICE

152,149

DESIGN FOR A DOLL

Alex Fine, St. Paul, Minn., assignor to Stuart Inc.,
St. Paul, Minn., a corporation of Minnesota

Application February 6, 1947, Serial No. 136,730

Term of patent 14 years

(Cl. D34—4)

To all whom it may concern:

Be it known that I, Alex Fine, a citizen of the United States, residing at Saint Paul, in the county of Ramsey and State of Minnesota, have invented a new, original, and ornamental Design for a Doll, of which the following is a specification, reference being had to the accompanying drawing, forming part thereof.

Fig. 1 is a front view of a doll, showing my new design;

Fig. 2 is a side view of the doll, shown in Fig. 1 as seen from the right side thereof; and,

Fig. 3 is a rear view of the doll, shown in Fig. 1. I claim:

The ornamental design for a doll, as shown.

ALEX FINE.
